UNITED STATES PATENT OFFICE

WILLIAM H. VE BELLE, OF PHILADELPHIA, PENNSYLVANIA

NECKTIE

Application filed August 22, 1932. Serial No. 629,974.

This invention relates to a necktie for use with either soft or stiff collars, the general object of the invention being to provide the necktie with a permanent knot forming portion so formed that the tie can be easily and quickly put in place and removed and one which will stay in adjusted position after once being adjusted.

This invention also consists in certain other features of construction and in the combination and arrangement of the several parts to be hereinafter fully described, illustrated in the accompanying drawing and specifically pointed out in the appended claims.

In describing the invention in detail, reference will be had to the accompanying drawing wherein like characters denote like or corresponding parts throughout the several views, and in which:

Figure 1 is a fragmentary front view of the improved tie.

Figure 2 is a similar view looking towards the rear thereof.

Figure 3 is an enlarged detail view showing the part of the tubular portion pulled from over the knot forming portion.

Figure 4 is a front view showing the tubular portion partly pulled over the knot forming portion.

Figure 5 is a rear view of a knot forming part before the same is bent.

Figure 6 is a top plan view of Figure 5 showing the tie material attached to the cross piece of the wire member.

Figure 7 is a fragmentary view partly broken away to show the reinforcing fabric.

Figure 8 is a view of one form of the wire member.

Figure 9 is a view of another form thereof.

In the drawing, the numeral 1 indicates a member formed of canvas or the like with its upper end rounded and its side edges diverging upwardly with the ends of the canvas folded upon the rear part of the major portion thereof so that the member formed by the canvas is of double thickness as shown. The folded portions are stitched to the major portion by the downwardly converging lines of stitching 2 and a member 3 of wire or the like is associated with the canvas member.

This wire member is bent to provide the straight central portion 3' and the hook portions 3'' at the ends of the straight portion with the free limbs of the hook portions extending downwardly while the hook forming portion extends upwardly as shown. These hook portions 3'' are placed in the casings formed at the ends of the member 1 by the lines of stitching 2 with the straight portion 3' extending through holes in the inner walls of the casings with the straight portion extending across the rear part of the member 1 as clearly shown in Figure 5. Thus the hook portions are held in the casing with the ends of the straight portion passing through holes in the casing so that the wire member is firmly attached to the canvas member.

The tie forming material 4 has an intermediate portion sewn to the straight part 3', as shown in Figures 3 and 6, the upper portion of the material is sewn to provide a tubular part 4' which is pulled over the member 1 as shown in Figure 4 to provide the knot forming portion of the tie. A narrow part 5 of the tie material has one end fastened to the part sewn to the straight portion of the wire member and this narrow part 5 is adapted to pass around the neck then to be passed through the knot forming part as shown in Figures 1 and 2, after said knot forming portion is bent into substantially tubular form as shown at A in Figures 1 and 2.

Reinforcing material shown at 5' is sewn to that part of the tie material which is connected with the wire member or adjacent the point where the material is fastened to the wire member so as to afford a support to the tie directly below the knot. This piece acts as a supplementary lining for the tie below the knot forming part.

If desired one of the limbs of the wire member can be extended and pointed as shown at 6 in Figure 9 and this point projected into the interior of the knot forming member so that the free end of the narrow strip 5 can be penetrated by the point so as to hold the strip 5 in adjusted position around the neck of the user.

When the canvas member 1 with the wire member 3 thereof is bent to form the knot A

which is covered by the tubular part 4' of the material; a flexible knot is provided which can be pressed into a shape to exactly simulate the knot of a hand tied neck tie and which 5 will hold the neckband 5 in place after the same has been adjusted around the neck of a user, and if desired the point 6 can be provided on the wire member to engage the free end of the neckband for holding it in 10 adjusted position. The wire form or member is automatically locked in position in the canvas member when said member is folded and stitched as shown in Figures 5 and 6 so that there is no danger of the wire member 15 becoming detached from the canvas member.

The tie material is not sewn to the canvas but is connected with the wire member. As before stated this tie can be used with either stiff collars or soft collars.

20 It is thought from the foregoing description that the advantages and novel features of the invention will be readily apparent.

It is to be understood that changes may be made in the construction and in the combination and arrangement of the several parts provided that such changes fall within the scope of the appended claims.

Having thus described my invention, what I claim as new is:

30 1. A necktie of the class described comprising a member formed of stiff fabric having its ends folded upon itself, portions of its ends sewn to the major portion to provide a casing at each end of the member, a 35 member formed of wire and bent to provide a straight bar with upwardly extending hook portions the free ends of which extend below the straight bar, said hook portions being located in the casings with the straight 40 portion extending through holes in the casings, necktie material having an intermediate portion connected with the straight portion of the wire member and the upper part of said material being sewn into tubular form 45 to enclose the first mentioned member and the wire member to form a knot when the first mentioned member is bent into knot forming position and a neck band having one end connected with the straight part of the 50 wire with its other end adapted to be passed through the knot forming portion.

2. A necktie of the class described comprising a member formed of stiff fabric having its ends folded upon itself, portions of its 55 ends sewn to the major portion to provide a casing at each end of the member, a member formed of wire and bent to provide a straight bar with upwardly extending hook portions the free ends of which extend below the 60 straight bar, said hook portions being located in the casings with the straight portions extending through holes in the casings, necktie material having an intermediate portion connected with the straight portion of 65 the wire member and the upper part of said

material being sewn into tubular form to enclose the first mentioned member and the wire member to form a knot when the first mentioned member is bent into knot forming position and a neck band having one end 70 connected with the straight part of the wire with its other end adapted to be passed through the knot forming portion, and a reinforcing piece having its upper end connected to the straight part of the wire member 75 and forming a lining for a part of the tie immediately below the knot forming part.

3. A necktie of the class described comprising a member formed of stiff fabric having its ends folded upon itself, portions of its ends sewn to the major portion to provide a casing at each end of the member, a member formed of wire and bent to provide a straight bar with upwardly extending hook 80 portions the free ends of which extend below the straight bar, said hook portions being located in the casings with the straight portion extending through holes in the casings, necktie material having an intermediate portion 85 connected with the straight portion of the wire member and the upper part of said material being sewn into tubular form to enclose the first mentioned member and the wire member to form a knot when the first mentioned member is bent into knot forming position and a neck band having one end connected with the straight part of the wire 90 with its other end adapted to be passed through the knot forming portion, one of the limbs of the wire member being substantially pointed and projected into the inside of the knot forming member to engage the free end of the neckband to hold the same in adjusted position.

In testimony whereof I affix my signature.
WILLIAM H. VE RELLE.
